(57) **CLAIM**

The ornamental design for a lens protector for mobile phone as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a lens protector for mobile phone showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The Broken lines in the drawings are for the purpose of illustrating portions of the lens protector for mobile phone and form no part of the claimed design.

1 Claim, 8 Drawing Sheets
